UNITED STATES PATENT OFFICE

152,295

DESIGN FOR A TROLLING SPINNER

Vavrinice Simun, Detroit, Mich.

Application October 7, 1947, Serial No. 141,780

Term of patent 14 years

(Cl. D31—4)

To all whom it may concern:

Be it known that I, Vavrinice Simun, a citizen of the United States and resident of the city of Detroit, county of Wayne, and State of Michigan, have invented a new, original, and ornamental Design for Trolling Spinners, of which the following is a specification, reference being had to the accompanying drawings, forming part thereof.

Figure 1 is a perspective view of a trolling spinner showing my new design;

Figure 2 is a top plan view of said trolling spinner;

Figure 3 is a side elevation thereof;

Figure 4 is an end view thereof.

I claim:

The ornamental design for a trolling spinner, as shown.

VAVRINICE SIMUN.
